TAPE DRIVE

Robert V. Jones and Joseph F. Talerico, Poughkeepsie, N.Y., assignors to International Business Machines Corporation, Armonk, N.Y., a corporation of New York

Filed Apr. 14, 1966, Ser. No. 1,886

Term of patent 14 years

Int. Cl. D14—02

U.S. Cl. D26—5

FIG. 4

FIG. 2

FIG. 3

FIG. 4

FIG. 5

FIG. 6

FIG. 7

FIG. 1 is a right front perspective view of a tape drive embodying our new design;

FIG. 2 is a rear elevation view;

FIG. 3 is a top plan view;

FIG. 4 is a left side elevation view;

FIG. 5 is a fragmentary cross sectional view taken on lines 5-5 of FIG. 1;

FIG. 6 is a fragmentary cross sectional view taken along lines 6-6 of FIG. 1; and

FIG. 7 is a fragmentary cross sectional view taken along lines 7-7 of FIG. 1.

The dominant features of our new design reside in the portions shown in full lines.

We claim:

The ornamental design for a tape drive, as shown and described.
